UNITED STATES PATENT OFFICE.

ROBERT A. ILG, OF CHICAGO, ILLINOIS, ASSIGNOR OF ONE-HALF TO
THERESA ILG, OF CHICAGO, ILLINOIS.

PROTECTIVE DEVICE FOR VENTILATING-FANS.

No. 831,284.

Specification of Letters Patent.

Patented Sept. 18, 1906.

Application filed February 3, 1905. Serial No. 244,028.

To all whom it may concern:

Be it known that I, ROBERT A. ILG, a citizen of the United States, residing at Chicago, in the county of Cook and State of Illinois, have invented certain new and useful Improvements in Protective Devices for Ventilating-Fans, of which the following is a specification.

My invention relates to ventilating-fans of that type known as "direct-driven" fans, wherein the electric or other motor is applied directly to the shaft of the fan. Such fans are commonly located in openings in walls and serve the function of driving off the more or less foul or tainted air in the room to which they are applied. Where such fans are driven by electric motors applied directly to the fan-shaft, the current of air drawn off by the fan necessarily passes over and in contact with the frame and windings of the motor, and where this air is more or less charged with corrosive fumes and gases the latter exert an injurious effect upon the parts of the motor.

A leading object of my invention, therefore, is to provide a protective device for fan-motors, especially such as are employed in ventilating rooms or chambers wherein the air is necessarily impure, such as chemical and other laboratories, paint-shops, kitchens, foundries and machine-shops, and the like.

It is also a well-known fact that electric motors after they have been started in operation gradually lose a small percentage of their efficiency by reason of the heat developed in the windings and other parts of the motor. Where such a motor is mounted directly on a fan-shaft, this evil is of course somewhat mitigated, owing to the presence of the air-current, which is constantly flowing over and around the same, and the device of my present invention embodies as an important feature thereof means whereby such a cooling action of the motor is not only preserved but enhanced coexistently with the protective feature.

My invention in a preferred mechanical form is illustrated in the accompanying drawings, wherein—

Figure 1 is a central vertical section through a ventilating-fan equipped with my improvement. Fig. 2 is a side elevational view of the protective device detached, and

Fig. 3 is a front elevational view of the detached device.

Referring to the drawings, 5 may designate a wall having an opening 6, in which is set the usual annular fan-casing 7. As herein shown, the space to the right of the wall 5 may be assumed to represent the interior of a kitchen, laboratory, or other chamber to be ventilated, the space to the left of the wall representing the outer atmosphere or any other space into which the fan discharges.

8 designates the fan of the usual form and type, which is mounted on a suitably-journaled fan-shaft 9, disposed centrally of the casing 7. On the shaft 9 is directly mounted an electric motor, conventionally illustrated at 10, said motor being supported in an annulus 11, carried by a series of bracket-arms 12, 70 suitably fastened to the fan-casing 7 or to the wall 5 adjacent to the same.

Referring now to those parts wherein my invention resides, 13 designates a cylinder of sufficient size to surround the motor 10 with a considerable annular space therebetween, one end of said cylinder being closed by a removable cover or cylinder-head 14, which may be secured thereto by bayonet-joints 15 or in any other suitable or convenient manner, the cylinder and its cover themselves forming a device in the nature of a protective hood for the motor. The opposite end of the cylindrical portion of the hood has a series of outwardly-bent apertured ears or lugs 16, 85 whereby the hood may be rigidly secured, as by bolts or rivets 17, to the supporting-arms 12. Preferably, also, to the same end of the hood is secured an annular extension 18 in the form of a frustum of a cone, said extension being conveniently secured in place at the same time that the hood is applied to the motor by extending bolts or rivets 17 through ears or lugs 19, projecting radially of the member. Tapping the cylinder 13 near its outer end is an elbow-shaped pipe 20, the other end of which extends through the wall 5, preferably just below the casing-opening 6. The inlet end of said pipe is preferably provided with a guard in the nature of a strainer 100 21 to prevent the inflow of impurities from the outside.

The hood covering the motor is made of sheet metal, the outer surface of which is en-

ameled, which renders the hood proof against the deleterious effect of many corrosive gases.

When the fan is set in operation by the motor, the current of air drawn therethrough, as indicated by the arrows, passes over the hood, but entirely out of contact with the motor and its immediate supporting parts, whereby the latter are fully protected, the hood by its presence offering but a slight and practically negligible obstruction to the flow of the air-current. At the same time the fan sets up a strong suction-current through the lateral inlet-pipe 20 of the hood, which current impinges directly upon the motor and coming as it usually does from the outside atmosphere is cool and effects a much greater cooling of the motor than has heretofore been effected by its bath in the current of air under-going expulsion from the room or chamber being ventilated. I have found in practice that the cooling effect upon the motor thus obtained enhances the efficiency of the motor to a degree considerably in excess of the slight reduction of the ventilating effect upon the room produced by the presence of the hood.

Where the air, vapors, or gases discharged by the fan are lighter than the air outside the room or chamber, as is usually the case, the elbow-pipe 20 is located on the under side of the fan, as shown, so as to avoid the back-flow of the same through the elbow-pipe. Where, however, such air, fumes, or gases expelled by the fan are of greater specific gravity than the atmosphere into which they are forced, the location of the inlet-pipe 20 will be reversed, so as to lie above the fan, for the reasons already stated.

40 The inner extension member 18 of the hood, while rendering the protection afforded by the latter more complete, is not essential to its effectiveness for its intended purpose. The screen 21 in the inflow-pipe 20 may also be employed or omitted, as desired.

45 The hood may of course be made with its cylindrical portion 13 and end portion 14 integral, although I prefer to make the latter separable, as shown, since in that case the motor can be inspected, set up, and removed without disturbing the cylindrical portion of the hood and its inflow-pipe.

50 While I have shown and described a practicable and desirable mechanical embodiment of my invention, yet it is to be understood that the invention is by no means limited to the particular form and construction of apparatus hereinabove set forth, but may be varied, in respect to details within the general purview and principle thereof.

I claim—

1. The combination with an electric motor and a ventilating-fan mounted directly on the armature-shaft thereof, of a protective

hood of less diameter than and wholly in rear 65 of said fan surrounding said motor with its open end adjacent to the suction side of the fan, said fan being uncovered on its suction side whereby the current induced by the fan flows over said hood, and a suction-pipe leading 70 from a point exterior to the room or chamber containing the motor and tapping said hood, substantially as described.

2. The combination with an electric motor and a ventilating-fan mounted directly on the armature-shaft thereof, of a protective hood of less diameter than and wholly in rear 75 of said fan surrounding said motor with its open end adjacent to the suction side of the fan, said fan being uncovered on its suction 80 side whereby the current induced by the fan flows over said hood, and a suction-pipe leading from a point exterior to the room or chamber containing the motor and tapping said hood laterally of the motor, substantially as 85 described.

3. The combination with an annular fan-casing adapted to be located in an opening in the wall of a room or chamber, of an electric motor supported by and concentrically with 90 said fan-casing and having a ventilating-fan mounted directly on the armature-shaft thereof, a protective hood of less diameter than and wholly in rear of said fan covering the sides and inner end of said motor with its 95 open end adjacent to the suction side of the fan, the space between the open end of said hood and said fan-casing being open whereby the current induced by the fan flows over said hood, and a suction-pipe leading from a 100 point exterior to the room or chamber containing the motor and tapping said hood, substantially as described.

4. The combination with a ventilating-fan and a motor mounted on the shaft thereof, of 105 a protective device for said motor comprising a cylindrical member surrounding the motor, a removable cap or cover closing the end of said cylindrical member remote from the fan, and an annular member convergent toward the fan applied to the opposite end of said cylindrical member, substantially as described.

5. The combination with a ventilating-fan and a motor mounted on the shaft thereof, of 115 a protective device for said motor comprising a cylindrical member surrounding the same, a removable cap or cover closing that end of said cylindrical member which is remote from the fan, an annular member secured to the opposite end of said cylindrical member inwardly convergent or flaring toward the fan-shaft, and a suction-pipe leading from a point exterior to the room or chamber containing the motor and tapping said cylindrical member laterally to thereby induce a 120 cooling-current upon the motor, substantially as described.

6. The combination with an electric motor and a ventilating-fan mounted directly on the armature-shaft thereof, of a protective hood of less diameter than and wholly in rear of said fan surrounding said motor with its open end adjacent to the suction side of the fan, said fan being uncovered on its suction side whereby the current induced by the fan flows over said hood, a suction-pipe leading from a point exterior to the room or chamber containing the motor and tapping said hood, and a strainer in said suction-pipe, substantially as described.
